TIMING MECHANISM

Frank G. Nicolaus, Chicago, Ill., assignor to Raymond T. Moloney, Chicago, Ill.

Application July 1, 1938, Serial No. 216,953

14 Claims. (CL 200—92)

The invention relates to a timing device and more particularly an electro-mechanical timer useful for controlling a plurality of switches and circuits to determine respectively their time and period of operation.

It is desirable to provide such timer in simple, compact form, that will operate quietly and effectively, without getting out of order.

The main object of the invention is to provide an improved electro-mechanical timing mechanism.

Another object is to provide such a timer at a minimum of expense.

Still another object is to provide a timer in which the cycles of holding various electrical circuits effective may be predetermined, as desired.

Other important objects will become apparent to those skilled in this art as the disclosure is more fully made.

These desirable objects may be achieved by the illustrative embodiment herein disclosed, wherein an electric motor drives reduction gearing, which in turn through a friction coupling drives a set of cam wheels operating together as a unit, said wheels having notches, with the notches in all wheels offset angularly with respect to one another. Associated with each cam wheel is a respective spring blade switch in such a manner that the wheels control making and breaking of respective electrical circuits in which said switches are disposed. One cam wheel has associated with it the motor control switch and an electromagnetic lock device to stop the said wheel and all the other wheels intermittently as desired, there being an auxiliary mechanical variator turnable from the reduction gearing to control a switch and circuit for the electromagnetic lock device all as and for a purpose more fully to be described.

In the drawings showing a practicable example of the invention:

Figure 1 is a front elevational view of the improved timer unit;

Figure 2 is a cross sectional view taken along the line 2—2 of Figure 1, looking in the direction of the arrows;

Figure 3 is a top plan view of the timer unit;

Figure 4 is a cross sectional view taken along the line 4—4 of Figure 3, looking in the indicated direction, and showing the variator used to determine the cycles;

Figure 5 is a face view of a typical cam wheel; and,

Figure 6 is a detail, fragmentary cross section-

al view to show the friction drive for the cam wheel unit.

The timer embodies a suitable frame 10, an end of which suitably carries a sub-frame 11, said sub-frame in turn carrying an electric motor 12. Said motor is of a standard type having a rotor, not shown, which is connected to drive appropriate reduction gearing 13 supported within the frame part 11. The final gear of said gearing is fast on and drives a horizontal main shaft 14, one end of which is journaled in the frame 11 while the other end of the shaft is journaled in the opposite end of the main frame 10 and in fact extends therethrough with nuts 15 at the free end thereof. A spring 16 encircles this portion of the shaft and is under compression to exert a force against the end 17 of a sleeve 18 coaxially disposed loosely on the shaft as shown. Carried fast on the shaft 14 between parts of the sleeve 18 is a disk wheel 19 having arranged near its periphery and extending normal from one face thereof, six, parallel pins 20, said wheel with its pins turning in a vertical plane in which is positioned a normally open spring blade switch 21 having an end of one blade shaped best to be engaged by the pins 20. This switch 21 is carried from an insulated block 22 on a transverse support 23 carried by the frame 10, in the manner shown. The pin wheel 19 constitutes a mechanical circuit maker and breaker for circuit wires 24, 25, the wire 24 going to an electromagnetic device 26 carried in a bracket 27 attached to one end of the frame 10 by screws 28.

Looking at Figure 4, it will be seen that the pins 20 are angularly variously spaced with respect to one another. This uneven spacing, no two of which are alike, serves an important purpose in holding closed the circuit to said electromagnet 26. For this reason the pin wheel 19 may be termed a variator. The electromagnet 26 has a movable core 29 formed at its exposed free end with a detent 30, a spring 31 in the device acting normally to push outwardly on the core 29 in the well known manner.

This detent 30 normally rides against one face of a motor control cam wheel 32 having a single peripheral notch 33, said wheel being made of insulation material and carried loosely on the shaft 14, said wheel at angularly spaced intervals being formed with radial slots 34 in a circle corresponding to the relative path followed by the detent 30 so that as the wheel 32 turns the detent 30 is pushed by the spring 31 into the slots 34; of course, one at a time. When the detent 30 so enters a slot 34 it serves to lock the cam wheel 35

32 against further rotation. Eight additional cam wheels 35, by way of example, are also similarly, loosely carried on the shaft 14, each said wheel 35 having a cam drop off portion or notch 36, as indicated. Each wheel 35 will have its drop off portion of a length, depth and angular position varying from that of the others; all of these wheels being parallel and made of insulation material. Cross shafts or bolts 37 are passed through all of these wheels 32 and 35 to secure them together so that they must turn as a unit and keep their fixed relative positions with regard to their cam portions. Collars 38 serve as spacers around the shaft 14 between said cam wheels, as shown, and similar spacer collars 39 are disposed on the bolts 37 between these wheels. On the outside face of the wheel 32 is positioned a friction felt disk driver element 40 and on the outside face of the end wheel 35 is a similar driver element 41, the sleeve 18, through spring 16, serving to press all of these loose parts 35, 38 frictionally together, in an obvious manner.

Associated respectively with each cam wheel 35 is a spring blade switch 42, a similar switch being also associated with the first cam wheel 32. As seen in Figures 2 and 3 these switches are carried by insulated blocks 43 on the cross support 23, the lower blade of each said switch being formed best to ride the periphery of its corresponding wheel to keep the switches closed and also to cooperate with the drop off cam notch therein to open the switches.

From the switch 42 for the wheel 32 leads a wire 44 from one blade to a source of energy, indicated by the plug 45, while a wire 46 leads from the other blade thereof to a starting switch 47. A tap 48 goes from wire 46 to the motor 12 and from said tap 48 the wire 25, heretofore described, is lead to the switch 21. From the source of energy a wire 49 goes to the other side of the motor, and a tap 50 from wire 49 goes to one side of the coil 26, as shown best in Figure 1. From each of the switches 42, except the one for wheel 32, are lead respective, separate and individual circuits 51 to any electrical desired devices whatsoever, not shown, that may be included therein. This completes the detail description of the various parts.

50 In operation the plug 45 is connected with a source of energy and when the switch 47 is momentarily closed the motor 12 is energized and drives the gearing 13, shaft 14 and pin wheel 19. Thus, all wheels 35 and wheel 32 turn as a unit. 55 Consequently wheel 32 as it starts causes cam notch 33 to leave the end of the lower blade of the switch 42 to cause the latter to close as it rides the periphery of the said wheel 32. This keeps a motor circuit 48, 44, 49 closed to keep 60 the motor, shaft 14, and pin wheel 19 turning. The device 26 is normally deenergized since its control switch 21 is normally open. Consequently, the instant a slot 34 on wheel 32 presents itself to the detent 30 it is snapped by the spring 65 31 into said slot 34 to lock the wheel 32 and, of course, all wheels 35 therewith against turning. The friction elements 40 and 41 come into action to prevent damage while the shaft 14 continues to rotate under such circumstances.

70 It may be at the exact instant that the detent 30 is about to engage in a slot 34 that one of the pins 20 on the variator wheel 19 is engaging and closing the switch 21. If this should be so, of course, the circuit 24, 50, 49, 45, 44, 42, 48 and 25 75 is closed to energize the device 26 to retract the

core 29 and pin 30 so that the wheel 32 and, of course, with it the wheels 35 are free to continue turning. As the wheels turn the switches 42 are, at different angular points, opened by the various respective cam drop offs of the wheels so that the several circuits 51 are at different times and for various periods held energized. The variator control of pins 20 on switch 21 and lock device 30 further governs the timing and cycles in an obvious manner. By substituting a different wheel 19 for the one shown with different pin spacings or numbers thereof, a different timing effect can be had. When the detent 30 holds the wheel 32 and the other wheels 35 with it, the rotation thereof once more starts just as soon as a pin 19 acts to close switch 21 to release the lock 30. In this fashion we have a friction coupling drive in which the drive motor 12 remains energized whether motor control wheel 32 stands still or turns; that is, until said wheel 32 has completed one revolution and the notch 33 thereof acts finally to open the switch 42 to break the motor circuit. It will be recalled that the starting switch 47 was initially only momentarily closed and that after the motor started the switch 42 for wheel 32 kept the motor energized, so that when the switch 42 hits notch 33 it follows the motor becomes dead. It can now be seen that the wheels 35 under the control action of their respectively offset cam portions, the variator pins 30 20, and wheel 32, all cooperate to time the effectiveness and duration of the circuits for the motor as well as the circuits 51 for whatever purpose they may be used. Thus, the closed time for all wheel switches is varied. The wheels always 35 start, turn step by step, and complete one revolution back to the starting point and their stop. All wheels turn as a unit and stop as a unit. The cam wheel 32 has only one notch and the motor always returns the parts to this starting point. 40

From this detailed description it is now apparent that a novel timing mechanism has been provided which achieves the desirable objects herefore recited.

It is the intention to cover all changes and 45 modifications which do not depart from the spirit and scope of the invention.

What is claimed is:

1. In a timing mechanism comprising a frame, a shaft journaled therein, an electric motor including connections to drive the shaft, cam wheels loosely mounted on the shaft, friction means between the shaft and wheels to drive the latter, a switch for each wheel carried by the frame, each switch being held closed by the respective cam wheel periphery and being included in respective electric circuits, each wheel having a notch to cause opening of the corresponding switch and circuit, one wheel and corresponding switch serving to govern the operation of the motor, and means intermittently to interrupt the turning of said wheels through a single revolution thereof while the motor and shaft continue to run. 50

2. In a timing mechanism comprising a frame, a shaft journaled therein, an electric motor including connections to drive the shaft, cam wheels loosely mounted on the shaft, friction means between the shaft and wheels to drive the latter, a switch for each wheel carried by the frame, each switch being held closed by the respective cam wheel periphery and being included in respective electric circuits, each wheel having a notch to cause opening of the corresponding switch and circuit, one wheel and corresponding switch serving to govern the operation of the motor, and 55 means intermittently to interrupt the turning of said wheels through a single revolution thereof while the motor and shaft continue to run. 60

motor, and means acting on said one wheel to stop same and with it the other wheels while the motor and shaft continue to turn, and means controlled by the turning shaft to release said one wheel to enable further turning of the wheels, said motor coming to rest when said one wheel has made a complete revolution.

5. In a timing mechanism comprising a frame, a shaft journaled therein, an electric motor including connections to drive the shaft, cam wheels loosely mounted on the shaft, friction means between the shaft and wheels to drive the latter, a switch for each wheel carried by the frame, each switch being held closed by the respective 10 cam wheel periphery and being included in respective electric circuits, each wheel having a notch to cause opening of the corresponding switch and circuit, one wheel and corresponding switch serving to govern the operation of the 15 motor, and means acting on said one wheel to stop same and with it the other wheels intermittently while the motor and shaft continue to turn, and means turning with the shaft for causing release of the wheels at irregular intervals 20 for further turning, said motor coming to rest when the wheels have made a complete revolution.

4. In a timing mechanism comprising a frame, a shaft journaled therein, an electric motor including connections to drive the shaft, cam wheels loosely mounted on the shaft, friction means between the shaft and wheels to drive the latter, a switch for each wheel carried by the frame, each switch being held closed by the respective cam 25 wheel periphery and being included in respective electric circuits, each wheel having a notch to cause opening of the corresponding switch and circuit, one wheel and corresponding switch serving to govern the operation of the motor, and 30 means comprising an electromagnet having a spring urged core formed with a detent to engage a face of said one wheel and enter openings formed in said wheel to stop same intermittently to interrupt turning thereof while the motor and 35 shaft continue to turn, a circuit for said electromagnet, and a circuit maker and breaker turnable with the shaft to cause functioning of the electromagnet and movement of the detent to release the wheel with the openings for intermittent turning movement with the other wheels, said motor and shaft coming to a position of rest when the wheels have made one revolution.

5. In a timer, a frame, a shaft journaled therein, an electric motor having connections to turn the shaft, a cam wheel loose on the shaft, a friction coupling between the shaft and wheel to drive the latter, a circuit for the motor including a switch supported by the frame and engaging the periphery of the wheel to hold the circuit 50 closed and the motor running, said wheel having a notch therein to cause the switch to open, means for intermittently interrupting turning movement of the wheel without stopping the motor and shaft, and means operable from the shaft to 55 make the interrupting means ineffective.

6. In a timer, a frame, a shaft journaled therein, an electric motor having connections to turn the shaft, a cam wheel loose on the shaft, a friction coupling between the shaft and wheel to 60 drive the latter, a circuit for the motor including a switch supported by the frame and engaging the periphery of the wheel to hold the circuit closed and the motor running, said wheel having a notch therein to cause the switch to open, said wheel having angularly spaced openings therein, 65 other cam wheels loose on the shaft and turnable

with the first mentioned wheel, means tying all of said wheels together, means for intermittently interrupting turning movement of the wheels without stopping the motor and shaft, switches and circuits individually associated with each of said other wheels, and means controlled by the turning shaft to cause turning of said wheels after their movement has been interrupted.

7. In a timer, a frame, a shaft journaled thereon, an electric motor including connections to drive the shaft, rotary circuit making and breaking means loosely carried on the shaft, friction drive means between the shaft and said means, means to lock the rotary means against turning while the motor and shaft continue rotation, and means controlled by the shaft to release the rotary means for further turning.

8. In a timer, a frame, a shaft journaled thereon, an electric motor including connections to drive the shaft, rotary circuit making and breaking means loosely carried on the shaft, friction drive means between the shaft and said means, means engageable with a portion of the rotary means at intervals releasably to hold same temporarily against turning while the shaft and motor continue to turn, and means operated by the shaft to cause release of the holding means at irregular intervals to produce irregular intermittent turning movement of the rotary means.

9. In a timer, a frame, a shaft journaled thereon, an electric motor including connections to drive the shaft, rotary circuit making and breaking means loosely carried on the shaft, friction drive means between the shaft and said means, a detent associated with the rotary means and 30 acting at intervals to engage and temporarily hold same against rotation, an electromagnetic device to release the detent to free the rotary means for further turning, a circuit for the device including a normally open switch positioned 35 adjacent the shaft, and a wheel turnable with the shaft having means to engage and close the switch momentarily to energize the device whereby the rotary means may again turn.

10. In a timer, a frame, a shaft journaled thereon, an electric motor including connections to drive the shaft, rotary circuit making and breaking means loosely carried on the shaft, friction drive means between the shaft and said means, a detent associated with the rotary means and 40 acting at intervals to engage and temporarily hold same against rotation, an electromagnetic device to release the detent to free the rotary means for further turning, a circuit for the device including a normally open switch positioned 45 adjacent the shaft, and a wheel turnable with the shaft having means to engage and close the switch momentarily to energize the device whereby the rotary means may again turn, said 50 wheel having a plurality of irregularly spaced pins extending therefrom, which pins coact with said switch to close same.

11. In a timer, a frame, a shaft journaled therein, an electric motor having connections to turn the shaft, a cam wheel loose on the shaft, a friction coupling between the shaft and wheel to drive the latter, a circuit for the motor including a switch supported by the frame and engaging the periphery of the wheel to hold the circuit closed and the motor running, said wheel having a notch therein to cause the switch to open, said wheel having angularly spaced openings therein, a spring pressed detent engaging the wheel and adapted to engage in said openings individually, thus locking the wheel while the shaft continues 75

to turn, and means controlled by the shaft to release the detent and free the wheel for further turning.

12. In a timer, a frame, a shaft journaled there-
5 in, an electric motor having connections to turn
the shaft, a cam wheel loose on the shaft, a fric-
tion coupling between the shaft and wheel to
drive the latter, a circuit for the motor including
a switch supported by the frame and engaging
10 the periphery of the wheel to hold the circuit
closed and the motor running, said wheel having
a notch therein to cause the switch to open, said
wheel having angularly spaced holes therein, a
spring pressed detent engageable in said holes to
15 lock the wheel with the shaft still turning, elec-
tromagnetic means to release the detent to free
the wheel, a circuit for the electromagnetic
means, and means operable from the turning
shaft for making and breaking said last circuit at
20 intervals.

13. In a timer, a supported continuously turn-

ing shaft, an electric motor to drive same, rotary
circuit making and breaking means loose on the
shaft, a friction coupling between the shaft and
means to drive the latter, means for temporarily
locking the first means at intervals against turn-
ing, and means controlled by the turning shaft
to unlock the first means at intervals for turn-
ing with the shaft. 5

14. In a timer, a supported continuously turn-
ing shaft, an electric motor to drive same, rotary 10
circuit making and breaking means loose on the
shaft, means for causing the first means to make
a single revolution and then come to rest with
the motor and shaft dead, a friction coupling be-
tween the shaft and first means to drive the lat-
ter, means for automatically and temporarily
locking the first means against turning, and means
controlled by the turning shaft for automatically
unlocking the first means at intervals for further
turning movement. 15
